ICEMAKER

Carl J. Knerr, Evansville, Ind., assignor to Servel, Inc.,
New York, N. Y., a corporation of Delaware

Application September 15, 1954, Serial No. 456,106

19 Claims. (Cl. 62—104)

This invention relates to automatic making, harvesting, drying, and storing of ice pieces, generally called ice cubes.

This invention relates particularly to ice makers like those disclosed and claimed in the copending patent applications of Sven W. E. Andersson, Serial No. 205,519, filed January 11, 1951, and of Harry C. Shagaloff, Serial No. 325,097, filed December 10, 1952.

Briefly, the above copending Andersson application discloses an ice maker wherein an ice mold, located in the freezing compartment of a household refrigerator, is divided into ice forming compartments, each having a generally arcuate contour so that pieces of ice may be readily turned or swept from the mold by relative turning movement between the mold and the ice pieces. The ice removing action is automatic, as is the filling of the mold, freezing, and loosening of the ice pieces. The ice pieces are detained for thorough drying before discharge to storage. The automatic operation is stopped short of discharge of ice to storage, and remains suspended during the time that a desired quantity of ice pieces is held in storage. In the specific structure disclosed in this Andersson application, power for operating the ice release and the control mechanisms is provided by a hydraulic motor which also measures and delivers a quantity of water to the ice mold for freezing.

The above copending Shagaloff application discloses an automatic ice maker wherein an ice mold and an ejector mechanism are located within the low temperature or freezing compartment of a household refrigerator. The ice mold is placed in thermal contact with a freezing shelf to which is attached a freezing coil, and the interior of the mold is divided into a plurality of ice forming compartments, each having a generally arcuate contour so that the ejector mechanism, which is mounted about the mold, may rotate through the ice forming compartments of the mold and sweep the ice pieces therefrom, in the same general manner as that disclosed in the above Andersson application. With the Shagaloff ice maker, one of the ice forming compartments of the mold is partially insulated from the freezing shelf and from the low temperature of the refrigerator in a manner that the water in this compartment is last to freeze and the ejector mechanism is energized responsive to the freezing of this water. The ice removing action is automatic, as is the filling of the mold, freezing, and loosening of the ice pieces. The ice pieces are detained on the ejector mechanism for thorough drying before discharged to storage. The automatic operation is stopped short of discharge of ice to storage and remains suspended during the time that a desired quantity of ice is held in storage. Power for operating the ejector mechanism and the control mechanism therefor is provided by a geared electric motor. This motor is of the type that will stall while energized when the ejector mechanism contacts the ice frozen solidly in the mold without burning out or otherwise harming the motor. The electric motor and the measuring vessel for supplying a measured quantity of

2

water to the ice mold are located on the rear exterior wall of the refrigerator.

The disclosures of the above copending patent applications of Sven W. E. Andersson and of Harry C. Shagaloff may be considered parts of this instant application and reference thereto may be made for detailed description of parts in common with the instant application.

A general object of this invention is to provide an improved method of and apparatus for automatically making, harvesting, drying and storing ice pieces.

More specific objects of the invention are:

To provide an improved ice mold for simultaneously freezing a plurality of pieces of ice;

To provide an improved heat transfer device and thermostat for sensing the temperature of water being frozen;

To provide an improved reset heater for the thermostat;

To provide an improved ejector mechanism for removing pieces of ice from freezing surfaces;

To provide an improved power transmission for the ejector mechanism with means incorporated therein for loading and unloading such transmission;

To provide a precision water metering device for measuring exact quantities of water to be frozen; and

To provide improved controls and safety cut-outs for an automatic ice maker particularly adapted for use with a household refrigerator.

The above and other objects and advantages of the invention are set forth in more technical detail in the following description and accompanying drawings, wherein:

Fig. 1 is an exploded perspective showing basic parts of the ice maker in accordance with this invention;

Fig. 2 is a longitudinal vertical section through the freezing compartment of a household refrigerator, showing the ice maker in side elevation;

Fig. 3 is a top plan of the ice maker, with parts in horizontal section, taken substantially on line 3—3 of Fig. 10;

Fig. 4 is a schematic wiring diagram of the controls for the ice maker;

Fig. 4A is a partial modification of the wiring diagram shown in Fig. 4;

Fig. 20 is a detail of parts of the microswitch, and cam mechanism for energizing the solenoid water valve.

General Description

Referring to Fig. 2 of the drawings, the ice maker, indicated generally by reference numeral 10, is located within the upper or freezing compartment 12 of a household refrigerator 14. The ice maker is inserted through an opening 15 in the rear wall of the refrigerator, which opening is closed by a closure member 16 attached by screws to said rear wall. The only parts of the ice maker that project beyond the closure member 16 is a water connection 103a and electrical connections T1 and T2, to be referred to in detail hereinafter. The front of the refrigerator is closed by the usual door 17. The freezing compartment 12 is cooled by a refrigerating coil 18 attached to the bottom wall thereof and forming an evaporator of a suitable refrigerating system, not shown. Resting on the bottom wall of the freezing compartment below and to the right of the ice maker, as viewed in Fig. 8, is an ice receptacle 19, adapted to receive and store ice pieces discharged from the ice maker. Only so much of the refrigerator as is necessary for a complete understanding of this invention is shown in the drawings.

Referring now to Fig. 1, the ice maker includes, generally, an ice mold 20, a mold heating element 30, a freezer shelf 32 upon which the mold is supported and which is cooled by a refrigerating coil 33, which coil is attached to the refrigerating system, not shown. The ice mold is surrounded at the sides, front and bottom by thermal insulation and the insulation is encased in an insulation housing, to be referred to in detail hereinafter. The rear ice-forming compartment of the ice mold is closed by a combined closure member and support 40, which member is formed of plastic, such as phenol formaldehyde, or other suitable thermal and electrical insulating material. An ejector mechanism 70 is mounted above the ice mold for rotary movement therethrough for sweeping the ice pieces therefrom, and is journalled at its front end in a bearing at the upper front end of the mold and at its rear is the rear closure member 40.

The rear closure member 40 is generally in the shape of a box, open at the rear and closed by a metal closure plate 41. The closure plate 41 supports three microswitches 140, 150 and 160, and provides bearing surfaces for a rear ejector shaft 76 and a timing gear shaft 86, to be referred to in detail hereinafter. Of the three microswitches, the microswitch 140 is operated by a cam 156 on the timing gear shaft 86 to deenergize and reenergize a compressor motor 180 (see wiring diagram, Fig. 4) of the refrigerator system and to establish and interrupt holding circuits, at the beginning and end, respectively, of an ice release cycle; the microswitch 150 is operated by the same cam 156 and this microswitch energizes and deenergizes a solenoid-operated water valve 100 (Fig. 3) for a precise number of seconds near the end of each ice release cycle; and the microswitch 160 is operated by a cam surface 156c on the front of cam 156, and acts as a cutoff to automatically deenergize the ice maker when the ice receptacle 19 is filled with a given amount of ice pieces. The microswitch 160 is adapted for manual operation, as pointed out hereinafter.

Mounted on the rear of the metal closure plate 41 is a gear housing 83, which contains and journals an ejector gear 77, a timing gear assembly 85 and a motor gear 82. The timing gear assembly is a form of Geneva movement,

to be referred to in detail thereafter. An electric motor 80 for driving the ejector mechanism and the controls therefor is mounted on the rear of the gear housing 83. This electric motor is geared down from 3400 R. P. M. to approximately 2.5 R. P. M. at its output shaft, and is of a type that stalls while energized when the ejector blades initially contact the ice frozen solidly in the mold, without burning out or otherwise harming the motor. A motor of this type is disclosed and claimed in a co-pending patent application of Sven W. E. Andersson, Serial No. 325,145, filed December 10, 1952.

Mounted on the right side of the ejector motor 80 (Fig. 3) is a precision solenoid-operated water valve 100. The inlet of valve 100 is connected to a suitable source of water under pressure, such as the house line, and the outlet is connected by a conduit 116 to the rear of a vertical passage 42 formed in the rear closure and support member 40, which passage discharges water through an outlet 42a (Fig. 1) into the rear ice-forming compartment of the mold. A mold thermostat 122 and a reset heater 130 for the mold thermostat, each to be referred to in detail hereinafter, are mounted on the rear of the ice maker.

Ice mold

Referring now to Figs. 1, 3 and 5 to 9, inclusive, the ice mold 20 comprises an aluminum die casting divided into a plurality of ice-forming compartments 21 by transverse partitions 22. The ice-forming compartments are generally semi-circular in transverse vertical section, and the partitions are tapered horizontally from the right to the left side thereof as viewed from the front in Fig. 3. For reasons pointed out hereinafter, the partitions have a slight taper in the vertical direction. The partitions are each provided with an upstanding projection 23 on the right side and with a weir or notch 24 in the left side thereof, as viewed in Fig. 8. A thermal insulator 25, made of nylon or the like, is fitted upon each of the upstanding projections 23 of the mold partitions. As shown in Fig. 8, and as pointed out hereinafter, the insulators 25 support one side of the ice pieces during the drying thereof, prevent the ice from sticking to the upstanding projections of the mold partitions and strip the ice pieces from the ejector mechanism should they become frozen thereto due to prolonged standing. The outer surface of each of the weirs 24 is of the same general curvature as the inner surface of the ice mold compartments, and the inner surface of the weirs is substantially vertical. As viewed in Fig. 3, the weirs are progressively smaller from the rear to the front of the mold.

Referring to Fig. 8, the ice mold is provided with an upstanding and offset flange 26 along the left side thereof, which flange is clamped in heat exchange relation with the left side wall of the freezing compartment 12 by a clamp 27 secured by a plurality of screws 27a, only one of which is shown in Fig. 8. The front and rear walls 28 and 29, respectively, of the ice mold slant outward from right to left, as viewed from the front in Fig. 3. The mold heater 30, in the form of a hairpin coil, is located in slots 31 in the bottom of the mold at each side thereof. The mold rests on the freezer shelf 32 that is cooled by the refrigerating coil 33 also is in the form of a hairpin. As shown in Fig. 8, the refrigerating coil is formed out of round for good thermal contact with the undersurface of the freezer shelf to which it is welded, or otherwise secured. The refrigerating coil 33 is connected to a suitable refrigerating machine, not shown.

As shown in Figs. 5 and 8, the mold is provided with a boss 34 projecting from the bottom rear thereof which passes through an opening in the freezer shelf, and which clamps the rear of the mold to the shelf by means of a thimble 35 held in place by a screw 36 threaded into the boss. The front of the mold is attached to the freezer shelf by a screw 37 threaded into the mold casting and provided with a washer 37a. The front of the mold is shaped

as shown in Fig. 1, and is provided with an integral boss 38 drilled to receive a bearing 38a (Fig. 5) made of nylon or other suitable thermal insulating material, and the bearing is provided with a filler 38b made of neoprene rubber, or like material. The filler 38b takes care of contraction and expansion of any water that may enter the bearing 38a as water vapor and freeze and thaw therein. The bearing 38a receives and supports the front end of the ejector shaft 71, to be referred to hereinafter. As shown in Figs. 3 and 9, the front ice-forming compartment of the mold is formed with an overflow duct 39 that insures against excess filling of the ice-forming compartments. With the precision solenoid water valve for filling the ice-forming compartments of the mold, to be described in detail hereinafter, the chances of excess filling from this source are rare; it is possible, however. Also, it is possible that an excess of thaw water may remain in the mold compartments at the end of an ejecting cycle, and this water may cause excess filling at the next filling cycle. Therefore, rather than have a possible overflow at the side of the mold, the overflow duct 39 is provided. In case of overflow, the duct 39 discharges into the ice receptacle 19 located beneath and to the right of the mold, as shown in Fig. 8.

Ice mold insulation

So as to confine the heat transferred to the refrigerating coil 33 to that extracted from the water in the ice mold compartments and transferred therefrom through the mold and the freezer plate 32 to the coil, and to add to the decorative appearance of the ice maker, the mold is provided with insulation and with decorative housing members at the sides, front and bottom thereof. The insulation members are made of unicellular sponge rubber that is impervious to moisture and, as shown in Figs. 1, 5, 8 and 9, include a right side member 51, a left side member 52, a front member 53 and a bottom member 54. The side and front insulation members are formed to fit the exterior contour of the ice mold, and the bottom insulation member is cut out (as shown in Fig. 1) to receive the refrigerating coil 33, the screws 36 and 37 for attaching the ice mold to the freezer shelf and a set of screws 64 for attaching this bottom insulation housing to the freezer shelf.

The insulation housing members, which are preferably made of a thermal insulating, moisture-proof and decorative material, such as white polystyrene, include a right side member 55, a bottom member 56 and a front member 57. The right side member (Fig. 8) is formed with an inwardly and upwardly projecting flange 58 adapted to fit within a groove 59 (Fig. 6) along the upper right side of the ice mold and with a lower inwardly extending flange provided with a groove 60 (Fig. 1) to receive the right upper edge of the bottom housing member 56. The bottom housing member 56 is dish-shaped, open at the back, and includes spacing ribs 61, which provide a space between this member and the bottom insulation member 54, and two openings 62 and 63, (Figs. 1 and 5) for access to the screws 36 and 37. This bottom housing member is attached to the freezer shelf by four screws 64, located at the front and back at each side thereof. Also, the bottom housing member 56 is provided with a channel 65 at the front left corner thereof (Figs. 1 and 9) to receive the lower end of the overflow duct 39 of the ice mold. The front insulation housing 57 is shaped as shown in Figs. 1 and 5 and is attached by a screw 66 to a bracket 67, which bracket is attached to the front upper portion of the ice mold by a pair of screws 68 (Figs. 3 and 5). The front closure member 57 is formed with access openings at the top and front thereof, and the front opening is closed by a decorative, spring-held disk 57a (Figs. 1 and 5). As shown in Fig. 2, the insulation housing members present a neat, decorative structure around the ice mold, and any moisture that may migrate

into the mold insulation during freezing periods is collected in the bottom housing member and drains therefrom through the openings 62 and 63 into the ice receptacle 19 during the ice thawing periods, as pointed out hereinafter.

Ejector mechanism

As shown in Figs. 3 and 5, the ejector mechanism 70 includes a front ejector shaft 71 mounted for clockwise rotation at its front end in the nylon bearing 38a at the front of the ice mold and at its rear end in a suitable bearing 71a (Fig. 1) located in the rear closure member 40, which member, as pointed out heretofore, is made of thermal insulating material. Extending tangentially (Fig. 8) from one side of the front ejector shaft 71, and formed integral therewith, is a plurality of ejector blades 72; there being one such blade for each ice-forming compartment 21 of the ice mold 20. The ejector shaft 71 is mounted in the plane of the longitudinal axis of the ice mold, and as shown in Fig. 8, is spaced from the upper edges of the mold partitions 22. At the rear, this ejector shaft is connected by a thermal insulating coupling 74 (Fig. 5) to a rear ejector shaft 76, which rear ejector shaft is connected to the ejector motor 80 by a novel timing gear assembly 85 (Fig. 1), to be described in detail hereinafter. As shown in Fig. 8, the outer upper edges of the ejector blades 72 cooperate with the insulators 25 in supporting the ice pieces above the ice mold for drying wetted surfaces thereof before discharge into the storage receptacle 19.

Power and timing mechanism

As pointed out heretofore, the electric motor 80 for driving the ejector mechanism 70 and the controls therefor is a stall motor equipped with internal gears (not shown) for reducing its speed from 3400 R.P.M. to approximately 2.5 R.P.M. at its output shaft 81. The motor field winding 80a and overload limit switch 80b are shown diagrammatically in Fig. 4. The motor output shaft 81 (Figs. 1 and 3) is formed with a square portion 81a upon which is keyed a gear 82. The motor gear 82 is meshed with a rear gear 87 of the timing gear assembly 85, which timing gear assembly is fixedly mounted on a shaft 86, journalled at its rear in a bearing 86a (Fig. 3) formed in the gear housing 83 and at its front in a bearing 86b formed in the metal closure plate 41 (Fig. 1). In front of the gear 87 (as viewed in Fig. 3) is a timing gear 88 having a toothed portion 88a and a blank portion 88b on the periphery thereof (Fig. 14). In front of the timing gear 88 (Fig. 3) is a timing cam 90 having a high portion 90a and a low portion 90b (Fig. 14) on the periphery thereof. The gears 87 and 88 and the cam 90 are held as an assembly by dowel pins 91. Fixedly mounted on the rear ejector shaft 76, and in mesh with the teeth of timing gear 88, is an ejector gear 77, and in front of the ejector gear (Fig. 3) and fixed to the rear ejector shaft 76 is an ejector cam 78 having a high portion 78a and a low portion 78b on the periphery thereof (Fig. 14).

The arrangement is such that upon rotation of the ejector motor 80, the motor gear 82 (Figs. 3, 13 and 14) rotates the rear gear 87 of the timing gear assembly, which two gears have meshing teeth throughout the 360° of their periphery, and rotation of the gear 87 causes rotation of the timing gear 88 and of the timing cam 90. As the timing gear 88 is rotated, the toothed portion 88a thereof is brought into mesh with the teeth of the ejector gear 77, which latter gear is provided with teeth throughout the 360° of its periphery, whereupon the ejector gear 77, the rear ejector shaft 76, the ejector cam 78 and the front ejector shaft 71 are rotated in unison. Rotation of the ejector gear 77 continues (neglecting for the present the stalling of the ejector mechanism by contact of the ejector blades 72 with the ice frozen solidly in the mold compartments) until the blank portion 88b of the timing gear 88 is juxtaposed with the teeth of the ejector gear 77 at which time the high portion 90a of the timing cam 90 is in

mesh with the low portion 78b (Fig. 14) of the ejector cam 78, whereupon the ejector gear 77 and shafts 76 and 71 are held stationary while the ejector motor 80, the motor gear 82, and the timing gear assembly 85 and cam 90 continue to rotate for a definite period before the motor is deenergized. Thus the ejector motor is unloaded during this period of an ejecting cycle, and during a portion of this period when the motor is unloaded, the solenoid valve 100 is energized to refill the ice mold with water, as pointed out hereinafter. During a freezing cycle of operating, the timing gear 88 and the ejector gear 77 are substantially in the relative positions shown in Fig. 14 with the high portion 90a of cam 90 in contact with the low portion 78b of cam 78. Thus the ejector mechanism is locked in the position shown in Fig. 8 for drying the ice pieces resting thereon.

Water metering and mold filling mechanism

Mounted on a bracket 101 on the side of the ejector motor 80 is the solenoid-operated water valve 100 (Figs. 3 and 12). This valve is a precision mechanism, in that it accurately meters a definite quantity of water therethrough when open; the opening and closing of which is accurately timed as pointed out hereinafter. Referring now to Fig. 15, this valve includes a body member 102 having an inlet connection 103 and an outlet connection 107 (Fig. 12). The inlet connection is provided with a nipple 103a that extends through the rear closure plate 16 (Fig. 2) for connection to a suitable source of water under pressure, such as the house line, and the outlet connection is connected to the ice mold, as pointed out hereinafter. In the passage 102a in the valve body 102, between the inlet and outlet connection, there is located a filtering screen 104, and a combined pressure regulator and valve seat 105 having a relatively small passageway 106 therethrough. Mounted on the body member 102, as by a bracket 109, is a solenoid which includes a winding 110 and a core 111, on the bottom of which core is a conical valve 112 adapted to register with and close the passageway 106 in the rubber pressure regulator and valve seat 105. The valve is biased to closed position by a compression spring 114.

A tube 116 leads from the outlet connection 107 of the valve, is bent in the manner shown in Fig. 12 and opens into the vertical passageway 42 (Fig. 3) formed in the closure member 40 at the rear of the ice mold. As shown in Figs. 1 and 11, the vertical passageway 42 has a lower outlet opening 42a above and to the rear of the rear ice-forming compartment of the ice mold, and, so as to prevent siphoning, the top of passageway 42 is open to the ambient. The water tube 116 is preferably formed of a thermal insulating material and a material by which the tube may be bent or formed into the shape shown in Fig. 12, and held in that shape without any kinks or other obstructions therein. An excellent material for forming this tube is polyethylene. As shown in Figs. 2, 3 and 12, the part of the water tube 116 that contains water during a freezing cycle of the ice maker is in the insulation space of the refrigerator and is not subjected to the freezing temperatures of the ice mold or of the freezing compartment 12 of the refrigerator. A filler member 13 (Fig. 2) located in the space between the rear of the freezing compartment 12 and the rear inner wall 14a of the refrigerator surrounds the rear closure member 40 of the ice maker, and, after the ice maker has been inserted as a unit into the refrigerator through the opening 15 in the rear insulation and the cover 16 applied, the space around the rear of the ice maker is filled with blown insulation (not shown).

Controls

As shown in Figs. 1 and 5, and as pointed out heretofore, the rear ice-forming compartment of the ice mold casting is open and is closed by the rear closure and support member 40, which member is formed of a plastic, such as phenol formaldehyde that is a good thermal and

electrical insulation. Integrally formed on the front face of the closure member 40 is a raised portion that fits into the rear of the ice mold and forms the rear wall 29 of the rear ice-forming compartment. The rear wall 29 is provided with an insulator 25a (Figs. 1 and 3), similar to the insulators 25 on the upper edges of the mold partitions 22. A gasket 29a seals the rear outer surface of the mold casting against the adjacent front surface of the closure member 40. The purpose of the insulating rear wall 29 of the ice mold is to make sure that the water in the rear ice-forming compartment is last to freeze, and complete freezing of the water in this rear compartment is utilized to energize the ice release mechanism, as disclosed and claimed in the above copending patent application of Harry C. Shagaloff, Serial No. 325,097, filed December 10, 1952.

For this purpose, in accordance with the instant invention, and as shown in Figs. 5, 7 and 16, a metal insert 120, preferably of aluminum, is embedded in the rear wall 29 of the ice mold formed on the closure member 40. This insert comprises a cylindrical plug 120a, having its front surface in contact with water to be frozen in the rear ice-forming compartment of the mold, an annular V-shaped groove 120b midway its length, into which the plastic is molded, and an integral disk 120c formed on its rear. The center of the upper half of disk (Fig. 7) coincides substantially with the longitudinal axis of the cylindrical plug and the true center of the disk is provided with a threaded opening 120d. The sensing element 124 of the mold thermostat 122, is, as shown in Figs. 5, 7 and 18, formed as a flat coil of approximately the same diameter as the diameter of the disk 120c. This sensing element, which is in fact the otherwise free end of a capillary tube 123 of the thermostat 122, is clamped against the disk 120c by an aluminum adapter plate 125 held in place by a screw 126 threaded into the opening 120d in the disk. The thermostat 122 is clamped to the rear of the metal closure plate 41 (Fig. 12) by the bracket 101, and is provided with an adjusting dial 122d.

As in the above Shagaloff patent application Serial No. 325,097, the mold thermostat 122 includes a diaphragm system that operates above atmospheric pressure and instigates an ice release cycle on falling pressure, while at the same time, if the pressure falls below normal, instigation of a subsequent release cycle is prevented. The thermostat must be reset before an ice release cycle can be completed. Thus, if the thermostat loses its charge or is otherwise inoperative and the thermostat switch 122a (Fig. 4) is not reset to the full line position before the switch blade 150a is moved to the broken line position, the ice maker stops with the water valve closed, as described hereinafter.

A reset heater 130 (Figs. 5, 7 and 16) for resetting the mold thermostat, is clamped to the adapter plate 125 for transferring heat to the sensing element 124 of the mold thermostat. The reset heater 130 includes an aluminum heat conductor 131 formed with a disk portion 131a at its front end (Fig. 7) and a grooved cylinder portion 131b extending rearwardly therefrom, into which grooves a pair of resistance wires 132 and 133 are wound. The heating ends of the resistance wires 132 and 133 are joined by a bi-metal high temperature or limit switch 134, shown in its normal or closed position in Fig. 17. An electrical insulating disk 135 is placed between the rear of the heat conductor 131 and the front of the limit switch 134. The reset heater is encased in a cup-shaped housing 136, formed with lugs 137 on opposite sides thereof and attached to the adapter plate 125 by a pair of screws 138 (Fig. 16). The housing 136 is preferably formed of phenol formaldehyde or other suitable thermal and electrical insulating material.

As shown in Fig. 17, the high temperature limit switch 134 includes a bi-metal element 134a held at its center in an insulating housing 134b. Embedded in the insulating housing is a pair of terminals 134c, each having one end thereof in position to be contacted by the bi-metal ele-

ment 134a and each having a spring clip 134d to receive the resistance wires 132 and 133. As shown in Fig. 5, the wires 132 and 133 of the reset heater and the capillary tube 123 of the mold thermostat are encased in a sleeve 139 made of vinyl or other suitable insulating material. With this arrangement, the mold thermostat 122 is influenced only by the temperature of the sensing element 124 and not by ambient temperatures. The sensing element, in turn, follows the temperature of the water in the rear ice-forming compartment of the mold during freezing cycles, and the temperature of the reset heater 130 during thawing cycles. As shown in the wiring diagram in Fig. 4, the reset heater 130 and the limit switch 134 are connected in series with the mold heater 30.

Referring now to Figs. 3, 10 and 11, the micro switch 140, that deenergizes and reenergizes the compressor motor 180 (shown only in the wiring diagram in Fig. 4) at the beginning and end, respectively, of an ice release cycle, is mounted by a pair of screws 142 upon a bracket 143, which bracket in turn is welded or otherwise secured to the metal closure plate 41. This micro switch includes a spring-pressed plunger 141 that is urged into contact with a cam 156, to be described in detail hereinafter, and when in contact with the high portion of the cam as shown in Figs. 10 and 11, which is the stationary position of the cam during an ice freezing cycle, the switch is in the full line position shown in Fig. 4 and the compressor motor 180 is energized; whereas shortly after the beginning of an ice release cycle, the high portion of the cam 156 leaves the plunger 141, and the switch 140 is shifted to the broken line position (Fig. 4), whereupon the compressor motor is deenergized, and remains so until near the end of an ice ejecting cycle when the high portion of the cam 156 again contacts the switch plunger 141 and returns the switch 140 to the full line position. As pointed out hereinafter, with certain installations it may be desirable to continue operation of the compressor motor during ice release cycles. In which case, the compressor motor 180 is connected directly to the conductor T2 (Fig. 4A) and the micro switch 140 is used only to establish and interrupt holding circuits.

Referring to Figs. 10, 11 and 20, the second micro switch 150, that energizes and deenergizes the solenoid valve 100, is also mounted on the closure plate 41 by a bracket and a pair of screws 152. This switch 150 includes a plunger 151 operated by a lever 153. This lever 153 is pivoted near its lower end (Fig. 20) on a post 154, and its upper or free end is bifurcated to receive a roller 155. The roller rides upon the cam 156 and is urged into contact therewith by a compression spring 157. The cam 156 (as best shown in Figs. 3 and 20) comprises a front portion 156a fixedly mounted on the timing gear shaft 86 and a rear portion 156b adjustably mounted by a set screw 158 upon the shaft 86. The purpose of this adjustment is to vary the combined length of the high or camming surfaces of the front and rear portions of the cam; the combined length of which high portions of the cam determine the length of time that the solenoid valve 100 is energized and water flows therethrough to the ice mold. In the particular embodiment disclosed, the cams 156a and 156b may be adjusted to hold the solenoid valve energized, and therefore open, for a period of from 10 to 12 seconds. This adjustment, which is made at the factory during assembly of the ice maker, is to take care of any slight variations in the ejector motor, the gear assembly and/or the solenoid valve. It is to be noted that the plungers 141 and 151 of micro switches 140 and 150, respectively, are operated by the same cam 156, and during an ice freezing cycle the switches 140 and 150 are in the full line positions (Fig. 4) with the compressor motor energized and the solenoid valve deenergized.

Referring again to Figs. 3, 10 and 11, the micro switch 160, that automatically deenergizes the ice maker when the ice receptacle 19 (Fig. 8) is filled with a given amount of ice pieces, is mounted on a bracket 162, the lower end

of which is attached by a screw 163 to the metal closure plate 41, and the upper end of which is adjustably connected to the closure plate by a screw 164 having a compression spring 165 (Fig. 3) thereon. The micro switch 160 includes a spring-pressed plunger 161 operated by a cam 166 mounted on a shaft 167, which shaft is journaled at its ends in partition walls 43 and 44 of the rear closure member 40. The purpose of the adjusting screw 164 is to center the plunger 161 below the cam 166 (Fig. 19). A lift arm 170 (Figs. 3 and 11), including a sleeve 171 with a roller 172 attached thereto by a shoulder screw 173, is fixedly and adjustably mounted on the shaft 167, near the partition wall 43. A second sleeve 174 is attached to the opposite end of the shaft 167 and a stop-arm 175, made of stainless steel or other relatively rigid material, is attached at one end to sleeve 174. The stop-arm is formed with an off-set near its attached end (as shown in Figs. 1 and 3) and is provided with a relatively heavy metal ball 176 on its free end. The lift arm 170 is raised by a cam member 156c formed on the front surface of the cam 156.

The arrangement is such that upon rotation of the timing gear assembly 85 the high portion of the cam 156c is brought into contact with the roller 172, whereupon the shaft 167 is rotated in a clockwise direction (Fig. 19) through a given arc. This clockwise rotation of the shaft 167 brings the high portion of cam 166 into contact with the switch plunger 161, which depresses the plunger and opens the switch 160 (Fig. 4), thereby opening a circuit to the ejector motor 80 in which this switch is contained. Clockwise rotation of the shaft 167 also lifts the stop-arm 175 and attached ball 176 from the full line position (Fig. 2) to the first or intermediate broken line position. Continued rotation of the timing gear assembly 85 (Fig. 3) causes the high portion of cam 156c to leave the roller 172 on the lift-arm 170, whereupon, assuming that the ice receptacle 19 (Fig. 8) is not yet filled with ice pieces, the ball 176 falls by gravity and through the arm 175 rotates the shaft 167 counterclockwise to its normal position which removes the high portion of cam 166 from the switch plunger 161, and this in turn causes the switch 160 to return to its closed position (Fig. 4).

Should the ice receptacle 19 be filled with the desired amount of ice pieces when the arm 175 is lifted, gravity movement of the ball 176 and stop-arm 175 is blocked by the ice, causing the switch 160 to remain open after the high portion of cam 156c has left the lift-arm 170 and until some ice has been removed from the receptacle 19. So as to adjust the travel of the shaft 167, cam 166, stop-arm 175 and ball 176, the lift-arm 170 is adjustably fixed to the shaft 167 by a pair of screws 177 (Figs. 1 and 11), access to which screws may be had by removing the spring-held button 178 from the front of the closure member 40 (Figs. 1 and 19). To insure against accidental piling up of ice pieces along the left side of the mold (Fig. 8) and interfering with the operation of the ejector mechanism, the ball 176 is made to travel in a path relatively close to the side of the mold by the offset in the stop arm 175. Should ice pieces so tend to pile up, gravity movement of the ball and stop arm is blocked, whereupon the ice maker is deenergized.

Mounted on the top wall of the freezing compartment 12 of the refrigerator (Figs. 2 and 8) directly above the stop-arm 175 is a spring clip 179. With this arrangement, the ice maker may be shut down and caused to stand idle at will by manually lifting the ball 176 and stop-arm 175 to the upper broken line position (Fig. 2) and engaging the arm in the spring clip 179. With the stop-arm 175 engaged in the spring clip 179, the ice maker will complete a freezing cycle, but, because the switch blade 160a of micro switch 160 is held in open position (Fig. 4) against a dead terminal 160c, a subsequent ice ejecting cycle cannot be initiated. Therefore, the ice maker stands idle with a batch of ice pieces frozen in the mold and a second batch of ice resting on the ejector

mechanism above the mold (Fig. 8) ready to be discharged into the storage receptacle 19. Operation of the ice maker may be resumed by manually removing the stop-arm 175 from engagement with the spring clip 179.

Wiring diagram

Referring to Fig. 4, T1 and T2 are the two sides of a 115 volt A. C. supply circuit, between which are connected by several circuits, the motor 180 for the refrigeration system, the micro switches 140, 150 and 160, the electric thermostat 122 for the ice mold, the ejector motor 80 with the motor field 80a and limit switch 80b, the mold heater 30, the thermostat reset heater 130 with limit switch 134, and the solenoid water valve 100. The full line position of the several switches in Fig. 4 is their normal position during an ice freezing cycle of the ice maker.

A first circuit (the only circuit for the compressor motor 180) includes the conductor T2, a movable switch blade 140a (in full line position) of micro switch 140, a stationary contact 140b, a conductor 200 in which is located a switch 190a of a thermostat 190 for the refrigerating system, the compressor motor 180, and T1. The sensing bulb 190b of thermostat 190 is placed in thermal contact with the refrigerating coil 18 (Fig. 8).

In installations where it is desirable to continue operation of the refrigerating system, and, therefore, of the compressor motor 180 during ice release cycles, the conductor 200' to the compressor motor may be connected directly to the conductor T2, as shown in Fig. 4A. In which case, the stationary contact 140b becomes a dead terminal and the micro-switch 140' is used only to establish and interrupt holding circuits, as described hereinafter. The remainder of the wiring diagram not shown in Fig. 4A is the same as that shown in Fig. 4.

Referring again to Fig. 4, a second circuit (a first circuit for the ejector motor 80) includes the conductor T2, a conductor 201, movable switch blade 160a (in full line position) of micro switch 160, a stationary contact 160b, a conductor 202, a stationary contact 122b, a movable switch blade 122a (in broken line position) of the ice mold thermostat 122, a conductor 203, a stationary contact 140c, a conductor 204, a stationary contact 150b, a movable switch blade 150a (in full line position) of micro-switch 150, a conductor 205, the motor field 80a, the motor limit switch 80b, a conductor 206, a conductor 207 and T1. A third circuit (second circuit for the ejector motor 80) includes the conductor T2, movable switch blade 140a (in broken line position) of micro switch 140, the stationary contact 140c, conductor 204, stationary contact 150b, movable switch blade 150a (in full line position), conductor 205, motor field 80a, motor limit switch 80b, conductor 206, conductor 207 and T1.

A fourth circuit (third circuit for the ejector motor 80) includes T1, movable switch blade 140a (in broken line position), conductor 203, movable switch blade 122a (in full line position), a stationary contact 122c, a conductor 208, conductor 205, motor field 80a, motor limit switch 80b, conductor 206, conductor 207 and T1.

A fifth circuit (a circuit for the mold heater 30 and the reset heater 130, is in parallel with each of the above circuits for the ejector motor 80 between the microswitch 150 and T1) includes a conductor 209, the mold heater 30, a conductor 210, resistance wire 132, limit switch 134 and resistance wire 133 of the reset heater 130, a conductor 211, conductor 207 and T1. This circuit to the mold heater and reset heater is energized when switch blade 160a is in full line position, switch blade 122a is in broken line position and switch blade 150a is in full line position, and when switch blade 140a is in broken line position and switch blade 150a is in full line position, and when switch blade 140a is in broken line position and switch blade 122a is in full line position. Thus, the mold heater 30 and reset heater 130 are energized at all

times that the ejector motor 80 is energized. Also, as pointed out heretofore, the reset heater 130 with its high temperature limit switch 134 is in series with the mold heater 130. With this arrangement both the mold heater 5 and the reset heater are automatically deenergized responsive to a given high temperature of the reset heater, which high temperature indicates that something has gone wrong with the circuits. For example, the overload switch 80b of the ejector motor may have opened, thereby stopping the motor 80 with the mold heater and reset heater 10 energized.

A sixth circuit (the circuit for the solenoid water valve 100 is in parallel with that part of the circuits for the ejector motor 80 between the microswitch 150 and the motor limit switch 80b) includes the movable switch blade 150a (in broken line position), a stationary contact 150c, a conductor 212, the coil 110 of solenoid 100, a conductor 213, the limit switch 80b of the ejector motor 80, conductors 206, 207 and T1. This is the only circuit 15 for the solenoid water valve and is energized only when the movable switch blade 140a is in broken line position, the movable switch blade 122a is in full line position, the movable switch blade 150a is in the broken line position, and the motor limit switch 80b is closed. The movable switch blade 150a is in the broken line position only 20 when the high portions of cams 156a and 156b (Figs. 10 and 11) are brought into contact with the roller 155 of micro-switch 150. The high portions of cams 156a and 156b are in contact with the roller 155 of micro-switch 30 150 only for a few seconds (10 to 12 seconds in specific embodiment disclosed) near the end of an ejecting cycle and at a time that the ejector motor is disconnected from the ejector shafts. If for any reason there should be an 35 electric power failure, or should the overload switch 80b of the ejector motor open when the switch blade 150a is in the broken line position, the solenoid is deenergized and the valve 112 (Fig. 15) is closed by the compression spring 114.

Operation

In operation, assuming that the several switches are in the full line position shown in Fig. 4, that the ice receptacle 19 (Fig. 8) is not yet filled with the desired quantity of ice pieces and that the stop-arm 175 is in the full line or lowermost position in Fig. 2; in other words, the ice maker is in operation. With the several switches in the full line position shown in Fig. 4, the compressor motor 180 is energized and water is being frozen in the several compartments of the ice mold. Due to the fact that the end wall 29 of the rear ice forming compartment of the mold is made of thermal insulating material, water in the rear ice forming compartment will be last to freeze, and when this water is completely frozen, the temperature on the surface 120a in contact with the water being frozen (26-28 F.) is reflected through the metal insert 120 (Fig. 55) to the sensing element 124 of the mold thermostat, whereupon the thermostat switch 122a is shifted from the full to the broken line position (Fig. 4). This shifting of the thermostat switch 122a establishes an initial circuit 55 from T2 through connector 201, stop arm switch 160a, 60 (in full line position) stationary terminal 160b, conductor 202, stationary terminal 122b, thermostatic switch blade 122a (in broken line position), conductor 203, stationary conductor 140c, conductor 204, stationary conductor 150b, switch blade 150a (in full line position), a conductor 205, motor field 80a, motor limit switch 80b, conductor 206, conductor 207 and T1, whereupon the ejector motor 80 is energized. The shifting of the thermostat switch 122a to the broken line position also establishes a parallel 65 circuit through the conductor 209, the mold heater 30, conductor 210, resistance wire 132, limit switch 134, and resistance wire 133 of the reset heater 130, conductor 211, conductor 207 and T1, whereupon the mold heater 30 and the reset heater 130 are energized.

Energization of the ejector motor 80 causes rotation of the motor, motor gear 82, timing gear 87, gear shaft 86,

timing gear 88, timing cam 90, and cam 156. The ejector motor 80 is otherwise unloaded during its initial energization. Running the ejector motor unloaded during the initial energization thereof is important in case the dried ice pieces (Fig. 8) are frozen to the ejector blades due to prolonged standing of the ice maker. Shortly after the cam 156 begins to rotate, the high portion of cams 156a and 156b leave the plunger 141 of microswitch 140, whereupon the movable switch blade 140a is shifted from the full to the broken line position in Fig. 4. This shifting of the switch blade 140a deenergizes the compressor 180 of the refrigerating system and establishes a holding circuit from T2 to T1 through the switch blade 140a (in broken line position), stationary contact 140c, conductor 204, stationary contact 150b, movable switch blade 150a, (in full line position) conductor 205, ejector motor 80, and conductors 206 and 207. This shifting of the switch blade 140a also establishes a holding circuit through the mold heater 30 and the reset heater 130. In installations when the conductor 200' is connected directly to the conductor T2, as shown in Fig. 4A, shifting of the switch blade 140a' to the broken line position has no effect on the operation of the compressor motor 180. With continued rotation of the ejector motor and the timing gear assembly, the cam surface 156c on the front of cam 156 is brought in contact with the roller 172 (Fig. 11) of the stop arm assembly 170, whereupon the shaft 167 is rotated clockwise (Fig. 19) with the result that the plunger 161 of microswitch 160 is depressed and the switch blade 160a is shifted from the full to the broken line position (Fig. 4). Rotation of the shaft 167 also lifts stop arm 175 and attached ball 176 to the first broken line position in Fig. 2.

At about this point in the rotation of the ejector motor and the timing gear assembly, the high portion 90a of cam 90 (Figs. 10 and 14) will have been removed from the low portion 78b of cam 78, and the toothed portion 88a of gear 88 will have meshed with the teeth of the ejector gear 77, whereupon the ejector gear 77, ejector shaft 76, ejector cam 78, coupling member 74 and the ejector shaft 71 with fingers 72 attached thereto are rotated in a clockwise direction (Fig. 8). This clockwise rotation of the ejector shaft 71 and attached fingers 72 causes the dried ice pieces that have been resting on the ejector fingers 72 and on the insulators 25 (Fig. 8) to be discharged over the side of the mold into the ice receptacle 19. Shortly after the batch of ice pieces have been discharged over the side of the mold, the timing mechanism will have rotated to the point that the high portion of cam surface 156c will have passed the roller 172 on stop arm assembly 170, whereupon the weighted ball 176 on stop arm 175 will fall by gravity (assuming that the ice receptacle 19 is not yet filled with ice pieces) and rotate the shaft 167 counterclockwise (Fig. 19) thereby removing the high portion of cam 166 from switch plunger 161 and returning switch blade 160a to the full line position (Fig. 4). Should the ice receptacle 19 be filled with the desired quantity of ice, at this point, the weighted ball 176 will be held up by the ice and the stop switch 160a will be held in the broken line or open position (Fig. 4). However, because of the holding circuit through switch blade 140a, (in broken line position) the ejecting cycle will continue to completion, but a new ejecting cycle cannot be initiated until some ice pieces have been removed from the storage receptacle 19 and the stop switch 160a closed.

The ejector motor continues to rotate until the ejector fingers 72 contact the ice frozen solidly in the several compartments of the mold, whereupon the ejector motor is stalled. However, the ejector motor 80, the mold heater 30 and the reset heater 130 remain energized, with the motor urging the ejector fingers against the ice so that the instant the ice is thawed free of the mold compartments, the motor 80 resumes its rotation and the ejector blades sweep the ice pieces from the mold and bring them for rest in the drying or upside-down

position shown in Fig. 8. The horizontal taper, in the transverse partitions 22 of the ice mold (Fig. 3) facilitates removal of the ice pieces from the mold compartments. However, in order to provide some resistance to removal of the ice pieces and thereby prevent any of them being flipped from the mold, the partitions are given a slight taper in the vertical direction, as shown in Fig. 5. By the time the ice pieces have been removed from the mold the reset heater 130 will have reset the thermostat switch blade 122a to the full line position shown in Fig. 4, the high portion of cam 166 on shaft 167 will have drawn away from the switch plunger 161 and the switch blade 160a will have returned to its full line position (Fig. 4), assuming that the ice receptacle 19 is not yet filled with ice and that the stop arm 175 and attached ball 176 have returned to the lower or full line position of Fig. 2.

By the time that the ejector motor 80 has rotated the ejector shaft 71 and attached ejector blades 72 to the position shown in Fig. 8, the toothed portion 88a of timing gear 88 (Fig. 14) will have left the teeth of the ejector gear 77, and the high portion 90a of timing cam 90 will be in contact with the low portion 78b of the ejector cam 78, whereby the ejector shaft 71 and attached fingers 72 are locked in the position shown in Fig. 8, and the ejector motor is again unloaded, although it continues to rotate. During this unloaded period of rotation of the ejector motor, the high portion of cams 158a and 158b will contact the roller 155 on switch arm 153, whereupon the plunger 151 of micro switch 150 (Fig. 20) is depressed and remains so depressed for approximately ten seconds during which time the switch blade 150a (Fig. 4) is in the broken line position and the coil 110 of the solenoid water valve 100 is energized, whereupon water in a metered quantity flows through the solenoid valve 100, the outlet tube 116, vertical passage 42 and outlet passage 42a (Figs. 8 and 11) into the rear ice forming compartment of the mold. From the rear ice forming compartment, the water flows through the notches 24 in the mold partitions to the forward compartments of the mold. The ejector motor 80 and the timing gear assembly continue to rotate unloaded, whereupon the high portions of cams 156a and 156b withdraw from the roller 155 of switch arm 153, thereby shifting the switch 150a back to the full line position which deenergizes and closes the solenoid valve 100. Shortly thereafter, the high portions of cams 156a and 156b will have returned to the positions shown in Figs. 10 and 11 with the plunger 141 of microswitch 140 depressed and the switch blade 140a shifted back to the full line position in Fig. 4, which ends the ejecting cycle and starts the next freezing cycle, with the ejector motor, the mold heater, the reset heater and the solenoid water valve deenergized, and with the compressor motor energized.

It is to be noted that with the switch blade 150a in the broken line position (Fig. 4), the only circuit to the coil 110 of the solenoid water valve 100 is from T2 through switch blade 140a (in broken line position), stationary contact 140c, conductor 203, switch blade 122a (in full line position) stationary contact 122c, conductor 208, switch blade 150a (in broken line position) stationary contact 150c, conductor 212, coil 110, conductor 213, limit switch 80b of the ejector motor, conductor 206, and conductor 207 to T1. Also, with the switch blade 150a in broken line position, the only circuit to the ejector motor 80, the mold heater 30 and the reset heater 130 is through conductor 208. Therefore, should the thermostat switch 122a fail to reset to the full line or warm position shown in Fig. 4 by the time the microswitch 150a has been shifted to the broken line position, the entire ice maker is rendered inoperative, with the ejector motor, the compressor motor, the mold heater, the reset heater and solenoid water

valve deenergized, and with the water valve closed. Inability of the reset heater 130 to reset the thermostat switch 122a is an indication that the thermostat has failed, lost its charge, and must be replaced before the ice maker can be rendered operative.

Also, it is to be noted that the coil 110 of the solenoid water valve 100 is wired in series with the overload limit switch 80b of the ejector motor, so that, should the switch 80b open for any reason as by overheating due to prolonged stalling or by motor failure, and stop the ejector motor while the high portion of cams 156a and 156b are in contact with the roller 155 of microswitch 150, thereby holding the switch blade 150a in the broken line position (Fig. 4) with the solenoid coil 110 energized and the water valve open, the coil 110 is immediately deenergized and the valve closed. Furthermore, the reset heater 130 with bi-metal limit switch 134 is wired in series with the mold heater 30, so that excess temperatures of both the mold heater and the reset heater are avoided. The limit switch 134 is set to open at approximately 135° F. and close at approximately 85° F.

Without further description it is thought that the novel features and advantages of the invention will be readily apparent to those skilled in the art to which this invention appertains, and it will, of course, be understood that changes in form, proportions and minor details of construction may be resorted to without departing from the spirit of the invention and scope of the claims.

What is claimed is:

1. In an automatic ice maker, an ice mold, electrically-operated means for filling the mold with water to be frozen, refrigerating means for freezing the water in the mold, an ejector mechanism including an electric motor for removing ice from the mold and for thereafter energizing said filling means, said electric motor having an overload limit switch in a circuit thereof, and said electric motor and said electrically-operated filling means being wired in an electric circuit with said overload limit switch in a manner as to deenergize both the electric motor and the electrically-operated filling means upon the opening of said limit switch.
2. An automatic ice maker as set forth in claim 1 wherein said electrically-operated filling means is a solenoid-operated water valve that is energized and deenergized responsive to rotation of said electric motor and wherein said valve is automatically closed upon the opening of the overload limit switch of said motor.
3. In an automatic ice maker, an ice mold, means for filling the mold with water to be frozen, refrigerating means for freezing the water in the mold, an ejector mechanism including an electric motor for removing ice from the mold, said electric motor having an overload limit switch in a circuit thereof, a control including a thermostat operative responsive to the freezing of ice in the mold for energizing said ejector mechanism, said overload limit switch and said thermostat being so constructed and arranged as to prevent operation of the filling means upon opening of the overload limit switch or failure of the thermostat.
4. In an automatic ice maker, an ice mold, means for filling the mold with water to be frozen, refrigerating means for freezing the water into ice in the mold, ejector mechanism for removing the ice from the mold, an electric motor for energizing and deenergizing the filling and refrigerating means and for driving the ejector mechanism, and timing mechanism connecting the electric motor with the filling means, the refrigerating means and ejector mechanism in a manner that the motor is unloaded when the refrigerating means is deenergized, loaded by the ejector mechanism and unloaded during the energization of the filling means.
5. In an automatic ice maker, an ice mold, means for filling the mold with water to be frozen, refrigerating

means for freezing the water in the mold, an ejector mechanism for removing the ice from the mold, said ejector mechanism including an ice-contact member movable into contact with ice in the mold for removing the ice therefrom, a motor for driving said ice-contact member and a timing mechanism connecting said motor to said ice-contact member, said timing mechanism having means therein to cause the motor to rotate unloaded for a first period, to connect the motor to the ice-contact member for movement thereof for a second period and to rotate the motor unloaded for a third period in a cycle of operation.

6. An automatic ice maker as set forth in claim 5 wherein said timing mechanism includes means for de-energizing the refrigerating means during the first unloaded period of rotation of said motor.

7. An automatic ice maker as set forth in claim 5 wherein said timing mechanism includes means for energizing said mold filling means during the second unloaded period of rotation of said motor.

8. An automatic ice maker as set forth in claim 5 wherein said timing mechanism includes means for energizing said mold filling means for a definite time interval during the second unloaded period of rotation of said motor, and means for varying the time interval during which the filling means is energized.

9. An automatic ice maker as set forth in claim 5 wherein said timing mechanism includes means for locking said ice-contact member in a stationary position during the unloaded periods of rotation of said motor.

10. An automatic ice maker as set forth in claim 5 wherein said timing mechanism includes means for de-energizing said motor and for locking said ice-contact member in a predetermined position during deenergized periods of the motor.

11. An automatic ice maker as set forth in claim 5 which includes a storage receptacle for receiving ice from said ice-contact member, and wherein said timing mechanism includes cut-out means for deenergizing said ice maker responsive to the accumulation of an optimum amount of ice in said storage receptacle.

12. An automatic ice maker as set forth in claim 11 wherein said cut-out means includes manually-operated means for deenergizing said ice maker at will.

13. In an automatic ice maker, an ice mold, a member mounted on the ice maker and movable through the mold for removing ice from the mold and for bringing such ice to rest for drying wetted surfaces thereof, and thermal insulating means cooperating with said member for supporting such ice while drying.

14. In an automatic ice maker, an ice mold, upright partition means for dividing said mold into a plurality of ice-forming compartments, means incorporated in the ice maker for removing ice pieces from the mold compartments and depositing such ice pieces on the upright partitions, and thermal insulating means on an upper portion of each of said partitions for receiving and supporting ice pieces removed from the mold for drying wetted surfaces thereof.

15. An ice maker comprising a freezing section, an ice storage bin, a heat exchange element in the freezing section on which liquid is frozen and from which ice is conveyed to the storage bin, means to cool said heat exchange element, and means for controlling the operation of said ice maker, said control means including a movable member biased to a position for operating the ice maker and movable to a position for stopping the ice maker, means for moving said movable member to stopping position during each delivery of ice to said storage bin and for returning said movable member to operating position after the delivery of ice to the storage bin provided the bin is not filled with ice, and means for holding said member in stopping position to thereby deenergize the ice maker regardless of the amount of ice in the storage bin.

16. An ice maker as set forth in claim 15 wherein said movable member is a lever biased by gravity to operating position, and wherein said holding means is a catch to retain the lever in stopping position regardless of the amount of ice in the storage bin.

17. In an automatic ice maker, a multi-compartment ice mold formed of metal and having one end wall thereof formed of thermal insulating material, means for filling said mold with water to be frozen, refrigerating means for freezing the water in the mold compartments, means for removing the ice from the mold, a metal insert embedded in said one end wall of the mold and having a first surface thereof in contact with water in one of the mold compartments and a second surface thereof accessible from the exterior of the mold, a thermostat operable responsive to the freezing of water in said one mold compartment for energizing said ice removing means, said thermostat including a sensing element in thermal contact with the second surface of metal insert, a diaphragm-operated switch portion remote from said sensing element and a capillary tube connecting the sensing element and the switch portion, and a reset heater having a first portion thereof in thermal contact with said sensing element and a second portion thereof in thermal contact with said capillary tube.

18. In an automatic ice maker, an ice mold, means for dividing the mold into a plurality of ice forming compartments, means for filling the mold with water to be frozen, refrigerating means for freezing the water in the mold, means for removing the ice from the mold and control means for said filling, freezing, freeing and removing means, said ice mold having a wall of one compartment thereof at least partially insulated from the freezing means whereby the water is completely frozen in the other of the plurality of compartments

before being completely frozen in said one compartment, a metal insert embedded in said wall and having a first surface thereof in contact with water in said one compartment and a second surface accessible from the exterior of said mold, said control means including a thermostat having a temperature sensing element in thermal contact with the second surface of said metal insert, a diaphragm-operated switch portion remote from said sensing element and a capillary tube connecting said sensing element and said switch portion, and a reset heater having a first portion thereof in thermal contact with said sensing element and a second portion in thermal contact with said capillary tube remote from said sensing element and a high temperature cut-out for said reset heater.

19. An automatic ice maker as set forth in claim 18 wherein the means for freeing ice from the mold includes an electric heater that is connected in series with the high temperature cut-out of said reset heater.
